(57) **CLAIM**

The ornamental design for a road lighting luminaire, as shown and described.

DESCRIPTION

1. Road lighting luminaire

Fig. 1.1 is a perspective view;

Fig. 1.2 is a right side elevation view;

Fig. 1.3 is a left side elevation view;

Fig. 1.4 is a front elevation view;

Fig. 1.5 is a rear elevation view;

Fig. 1.6 is a top plan view;

Fig. 1.7 is a bottom plan view.

The broken lines depicting portions of the bottom of the road lighting luminaire in the drawing are for illustrative purposes only and form no part of the claimed design.
